ARTHUR J. SHEA, OF MEMPHIS, TENNESSEE

METHOD OF BUILDING LEVEES AND EMBANKMENTS

Application filed August 18, 1928. Serial No. 300,506.

This invention relates to a method of building levees or embankments and relates particularly to a method for doing this where the cross-section of the embankment is such as to require transportation of the material from a somewhat remote point in order to secure sufficient material for the purpose.

In the building of a levee such as is used to prevent overflow of rivers, and typically such a levee as is used for the protection of alluvial lands along the Mississippi River, the base of the levee is often more than two hundred feet wide, the amount of ground which must be left untouched, adjacent the toe of the levee, is as much as one hundred feet in width and the borrow pit from which material is excavated to build the levee is comparatively shallow. It follows then that in order to get a sufficient amount of dirt from the borrow pit the pit must extend a distance of several hundred feet further away from the levee.

As the size of levees have been enlarged and these distances have increased it has become increasingly difficult to place the material excavated in the levee embankment, especially as the embankment approaches its maximum height, various expedients have therefore been resorted to for the transportation of the materials. All of these expedients have required either excessively expensive, and, what is even worse, cumbersome machinery, expensive and repeated rehandling of the material; or where the material has been economically transported has required the construction of a dumping trestle or incline, and the hauling of material up such trestle or incline which is slow and expensive.

The objects of my invention are to provide a method of handling the material, which method will improve upon prior methods, will reduce the cost and speed up the work. The way in which this object is accomplished and the manner of its accomplishment will readily be understood from the following specification on reference to the accompanying drawings, in which I have shown certain typical types of machinery and means of transportation by which the method herein-

after set forth may be accomplished and in addition have shown these as operated to build a typical river levee.

In the drawings Fig. 1, is a sectional elevation taken as on the line I—I of Fig. 2, showing typically one form of the machinery which must be employed;

Fig. 2, is a plan view showing a typical operation layout;

Fig. 3, is a sectional elevation on the line III—III of Fig. 2, looking in the direction of the arrow;

Fig. 4, is a reduced scale plan outlining a longitudinal pit and typical layout.

Referring now to the drawings, 10 is the levee or embankment which is being built. 11 is an elongated pit, or dump-pit, which in the case of a levee embankment ordinarily lies within the confines of the embankment, when same is completed, and which may so lie in the case of other embankments, though not necessarily so. This pit may lie transversely to the line of the embankment as shown in Fig. 2, or along the line of the embankment as shown in Fig. 4, in which latter case it would preferably be continuous; or it may lie at some other angle. The pit is preferably elongated in order that material may be dumped into it from one side over a considerable distance, whereby for instance a train load of dirt might be spotted along the side of the pit and a number of cars be dumped therein, or even in some cases the entire train load, without re-spotting. The pit is preferably comparatively shallow, with the side slope 12 as steep as the natural ground, in which the pit is dug, will stand up for the limited period of its use and with the opposite slope 13 much flatter. 14 is an excavator, which may be of any desired make or design, which excavator preferably does not require a track but may be shifted along the ground and which excavator may be used for digging the pit 11 and depositing the material therefrom in the proposed embankment, and thereafter may be used for removing dumped material from the pit and placing such material in the embankment.

Located adjacent the dump-pit 11, and lying substantially parallel to the length

thereof, is a railroad track 15 which extends laterally at such angle as may be desired to a point where material may be loaded to be transported to the dump-pit. 16 are dump cars and 17 a locomotive for handling the same. 18 is an excavator for loading the cars and 19 a borrow pit from which material is being secured for the embankment.

In the drawings a typical cross-section of 10 borrow pit and standard levee twenty feet in height is shown. Assuming for example such an embankment, roughly 2,000 cu. ft., of dirt would be required for each foot of embankment and the base width of the embankment 15 from toe to toe would be 180 feet. Between this toe and the borrow pit from which the dirt is taken, what is called a berm is required, which berm is often 100 feet wide. Requirement is made that the borrow pit 20 shall be shallow, and if as shown, it is restricted to an average five feet depth the necessary width of the borrow pit would be some 400 feet. In such an embankment a dump pit, say one hundred feet long and 25 five feet deep is dug, the ends of this pit lying well within the confines of the embankment. The pit is located at such distance from the end of the embankment that it may be reached by the bucket of an excavator positioned approximately half way between the embankment 30 and the pit, and in the line of progress of embankment construction. The track 15 is laid along the side of this pit most remote from the embankment and extended over to 35 the further side of the proposed borrow pit and preferably somewhat beyond the same. The excavator 18 is used to load dirt from the borrow pit into the cars 16, and thereafter the cars are moved alongside the dumping 40 pit and are dumped thereinto. The dirt so dumped is then picked up by the excavator 45 and placed in the embankment.

When the embankment encroaches on the 50 dump pit excavator, the latter is moved 45 toward the dump pit until further movement is impossible or at least undesirable, after which it may be shifted beyond the dump pit and a new pit dug, as indicated by the dotted 55 location 11X. The tracks are correspondingly shifted beyond the new dump pit, the 60 borrow pit excavator is likewise shifted, and the procedure repeated.

In some cases it is more convenient to bring 55 the track in from the borrow pit at an angle to the embankment in which case it might be more convenient to locate the axis of the 60 dump-pit at a corresponding angle.

It may be found expedient to substitute a 65 longitudinal dump pit for other forms of pit. In such case the pit may be excavated as far in advance as may appear desirable and be thereafter extended as shifts make it necessary. Such method is typified in Fig. 4, with the dump pit designated by the 70 numeral 20, and an extension thereof by the

numeral 20X. The track in this case preferably curves around until parallel with the pit.

It will be understood that only such detail as may be included in any claim shall be pertinent thereto, and that types of machinery indicated or means of transportation shown are illustrative only and unless specifically set out in a claim shall not form a limitation thereof.

Having described my invention what I claim is:

1. The method of building a levee or permanent embankment which comprises excavating a temporary dump-pit on the site of the proposed embankment, loading material at a remote point, transporting such material to and dumping same into said pit, removing the material from said pit and depositing it to form a levee or permanent embankment until said embankment encroaches on the dump-pit, and in then abandoning and filling the dump-pit with the excavated material and continuing the building of the embankment over said dump-pit.

2. The method of building a permanent embankment by longitudinal extension, which comprises excavating a temporary dump-pit lying within the area to be occupied by the embankment, excavating and transporting material to and dumping same into said pit, removing the material from the pit and placing same directly on said embankment, and as said embankment encroaches on said pit, then in advancing the pit in a line longitudinally of the embankment, and in successively filling the abandoned portion of the pit with the material excavated so as to continue the building of the embankment over the successively abandoned portions of the pit.

In testimony whereof I hereunto affix my signature.

ARTHUR J. SHEA.
